MARQUIS DE SALAMANCA, OF MADRID, SPAIN, ASSIGNOR TO SOCIETE ELECTRO-MECANIQUE D'APPAREILLAGE POUR L'ESSENCE, OF BOIS-COLOMBES, FRANCE.

UNLEAKABLE AND UNINFLAMMABLE GASOLINE TANK.

Application filed May 9, 1925, Serial No. 29,171, and in Belgium March 21, 1925.

Experience has proved that if the gasoline tank of an airplane is punctured by a bullet, the airplane is put out of action, either on account of losing its gasoline, or by the fire which generally occurs. It therefore becomes indispensable to preserve the existence of the airplane by protecting the tank from the danger which menaces it. In addition, it is advisable that the protective device be durable and of light weight.

The object of the present invention is to provide a protective covering complying with these primary conditions. The covering may be used on any gasoline tank, though it is specially intended for those used with airplane motors.

The covering in question is composed essentially of two layers of rubber of different quality, cemented together so as to form an indivisible whole. The inner layer facing the wall of the tank is of pure raw unvulcanized rubber, since this layer must be easily dissolved by the gasoline.

The outer layer is of very elastic vulcanized rubber.

It will be understood that immediately after the projectile has passed, the lips of the opening that the ball has made in the vulcanized rubber will close on account of the great elasticity of the latter, and the gasoline coming into contact with the raw layer will soften it and heal the cut.

The invention also provides for the use of ducts between the wall of the tank and the inner surface of the layer of unvulcanized rubber. These ducts serve first of all to preserve the rubber. In addition, they reduce to their lowest terms the effects of the "hammer" produced in the liquid by the passage of the projectile the gasoline drawn by the ball into the hole in the tank wall being suddenly thrown into the relatively large space formed by the duct. The gasoline sprays the sides of the latter and then flows along these sides while rising towards the bullet hole. Finally, by their presence the ducts reduce the weight of the covering.

In order to form the ducts, it is only necessary to introduce strips between the tank wall and the inner surface of the unvulcanized rubber, the strips consisting, for example, of any kind of rubber or of other material, placed at suitable intervals, and extending parallel to each other all around the tank. It is evident that since the flow of

gasoline along the sides of the ducts takes place by gravity, the arrangement of the ducts must facilitate such flow, but it is not limited either to a strictly vertical position of the ducts, or to a given form, or in the way in which the ducts are formed, the essential purpose of the strips being to simply serve as spacers.

Experience having demonstrated that a protective covering must have a certain thickness (at least 20 mm.) in order to give efficacious service, the invention provides for the formation of a covering having the required thickness simply by the superposition of coverings like that which has just been summarily defined and which will be clearly described further on in connection with an example of construction. By fixing these different covers solidly onto each other, a single multiple covering is formed having a sufficient thickness and channelled with ducts which lighten and air it, and which deaden the additional shock produced by the sudden movement of the liquid.

The accompanying drawing represents by way of example one of the forms of the invention.

Figs. 1 and 2 refer to a single covering. Fig. 1 represents a partial vertical section of a tank with the covering. Fig. 2 shows a section taken on the horizontal plane *c d* in Fig. 1.

Fig. 3 represents a horizontal section taken through a multiple covering.

In these figures, like or simply analogous elements are designated by the same numbers.

The tank wall is shown at 1, while 2 designates a coarse cloth with which the double layer of rubber is covered. This cloth serves for consolidating and rendering more intimate the contact between the layer 5 of very elastic vulcanized rubber with the inner layer 4 made of raw unvulcanized rubber, as pure as possible. The same cloth may also cover the tank wall proper, as is shown at 2'. The ducts, the multiple purpose of which has been defined above, are seen at 7 (Figs. 2 and 3). They are bounded by the side of the cloth 2' (or by the tank wall 1 if the cloth 2' is not used), by the layer 4 of raw rubber and by the strips 6 placed at suitable intervals between the layer 4 and the tank proper (or the cloth 2').

These strips extend entirely around the tank and are securely cemented to the rub-

ber 4. They may also be independent of the rubber. The section represented in Fig. 1 having been taken on a vertical plane the trace of which is *a b* on Fig. 2 and which 5 passes through an interval between strips, the strip 6 is not shown sectioned in Fig. 1. As has been stated it is advisable to place the strips approximately or exactly vertical, so as to facilitate the flow of the liquid.

10 The projectile having pierced the tank and having come out through the wall of the tank represented in the figures, will have entirely punctured the cloth 2 and the layer 4, as well as the layer 5, but the latter, on 15 account of its elasticity and its constricting action on the layer 4, will close the sides of the cut. The gasoline will slowly fill the pocket in the covering and will bathe the edges of the cut produced in the layer 4 20 of unvulcanized rubber, dissolving this rubber and healing the cut with the latter. The hole will be stopped automatically, as it were, simply by the dissolving action of the gasoline and the constricting action of the 25 layer 5.

The alternative form represented in section in Fig. 3 is constituted by the superposition, on the covering which has just been described, of a second covering concentric 30 with the former and composed of the same elements. Thus the strips 6, the unvulcanized rubber 4, the vulcanized rubber 5, the coarse cloth 2 and 2' are found again on the second covering.

35 Multiple coverings formed by several superposed concentric coverings constitute still other alternatives of the same invention and moreover represent it in the form the most suitable for the practical requirements, 40 since such multiple coverings have the necessary thickness in addition to the advantages characterizing the single covering described above.

The strips, the purpose of which consists 45 in forming the ducts, may have any shape and any section, provided that they can perform the essential duty assigned them. They may also be made of any material (in particular, they can be formed by ribs on the 50 layer of unvulcanized rubber 4), provided that the material of which they are made be neither harmful to the other substances entering into the composition of the covering, nor perishable. Finally, the relative 55 position of the ducts 7 formed in the successive coverings is unimportant, since the ducts in each covering do not necessarily have to line up with those in the adjacent covering.

For the layer 5, sheets of the vulcanized

rubber known as "inner tube" may be used 60 or any other lighter rubber having a coefficient of elasticity approaching that of the said sheets.

The raw unvulcanized rubber of which the layer 4 is made must be easily attacked and 65 dissolved by gasoline and must also be as pure as possible. Practically, the addition of foreign matter may be admitted, such as rosin, rendering the rubber softer and less sensitive to the cold. 70

What I claim is:

1. A protective covering for gasoline tanks including layers of rubber of different qualities, the first complete layer to be exposed to the wall of the tank and the gasoline which 75 may leak therefrom being of rubber readily dissolved by gasoline.

2. A protective covering for gasoline tanks including layers of rubber of different qualities, the first complete layer to be exposed to the wall of the tank and the gasoline which may leak therefrom being of rubber readily dissolved by gasoline, one of the 80 other layers being of vulcanized rubber and exerting a constricting action on the said 85 readily dissolved layer.

3. A tank having a protective covering comprising an inner layer of unvulcanized rubber directly facing the wall of the tank and exposed to immediate contact of petrol which may leak from the tank, and an outer elastic layer of vulcanized rubber exerting a constant constriction on said inner layer to cause the latter, when punctured and the edges of the cut therein have been dissolved 90 by leaking petrol, to close said cut and thereby prevent further leakage of the tank. 95

4. A tank having a protective covering comprising an inner layer of unvulcanized rubber directly facing the wall of the tank and exposed to immediate contact of petrol which may leak from the tank, and an outer elastic layer of vulcanized rubber exerting a constant constriction on said inner layer to cause the latter, when punctured and the edges of the cut therein have been dissolved by leaking petrol, to close said cut and thereby prevent further leakage of the tank, said inner unvulcanized layer being spaced from the wall by strips, said strips forming ducts therebetween facilitating contact of leaking petrol with the said inner layer. 100

5. A protective covering as in claim 1, with a netting interposed between the first rubber layer and the tank. 115

In witness whereof I affix my signature.

MARQUIS DE SALAMANCA.
